ALKALI-REFINING OF FATTY GLYCERIDES
IN THE PRESENCE OF AN INORGANIC
PHOSPHATE COMPOUNDS. Jack Rini, Winchester, Mass., assignor to Lever
Brothers Company, Cambridge, Mass., a cor-
poration of MaineNo Drawing. Application May 29, 1948,
Serial No. 30,176

7 Claims. (Cl. 260—425)

1

This invention relates to the alkali-refining of fatty glyceride stocks in the presence of a small amount of an inorganic phosphate compound, and especially in one embodiment to the alkali-refining of soybean oil in the presence of a small amount of tetrasodium pyrophosphate.

The alkali-refining of fatty glyceride stocks has long been practiced, an extensive information as to procedural details is available in the literature; e. g., "Industrial Oil and Fat Products," by Alton E. Bailey, Interscience Publishers, Inc., New York, N. Y., 1945, which described refining process, among others, that one characterized as the "dry" method and the "wet" method; "Vegetable Fats and Oils," by George S. Jamieson, Reinhold Publishing Corporation, New York, 1943. Generally, alkali-refining involves di-phasic separation of an aqueous phase containing undesirable impurities, and a refined oil phase. The phases may be allowed to separate by gravity, as in kettle refining, or may be separated by centrifugal means.

The art is confronted with the problem of minimizing refining losses, which are a serious factor in the large scale refining processes, especially in batch or kettle refining. The art regards the presence of organic surface active compounds in the oils, e. g., phosphatides in soybean oil, among other factors, as being associated with high refining losses.

In accordance with the invention, it has been found that the refining losses may be markedly reduced if the alkali-refining is carried out in the presence of an inorganic phosphate compound.

This invention is of great commercial significance, inasmuch as it permits alkali-refining in large scale conventional kettles with relatively low losses, e. g., comparable to those obtained by more costly centrifugal methods, to give a resulting product of satisfactory quality. The presence of the phosphate additive also tends to improve the centrifugal refining process, but, of course, the difference is not so marked since the losses in the centrifugal process are already relatively lower.

The objects achieved in accordance with the invention include the provision of methods of alkali-refining fatty glycerides with relatively low refining losses, wherein the refining is carried out in the presence of an inorganic phosphate compound; the provision of processes of alkali-refining soybean oil in the presence of a small amount of tetrasodium pyrophosphate; and other objects which will be apparent as details or em- 55

bodiments of the invention are set forth herein-after.

In order to facilitate a clear understanding of the invention, the following specific embodiments are set forth.

EXAMPLE 1

To a batch of degummed, solvent extracted soybean oil having 0.3% free fatty acid by weight on the oil, there is added 0.10% of tetrasodium pyrophosphate ($Na_4P_2O_7$) based on the weight of the oil, and in the form of a 10% aqueous solution, at room temperature and with agitation. Then there is added sodium hydroxide in an amount of 0.2% in excess of the stoichiometric amount required for neutralization of the free fatty acids in the oil, in the form of a 16° Bé. lye solution, at room temperature and with agitation (in accordance with usual procedures). Agitation is continued for 15 minutes. Then the temperature of the reaction mixture is raised to about 52° C., with continued agitation. Agitation is stopped and the batch is allowed to settle for 8 hours. The refined oil is removed from the settled foots, e. g., by means of a skim pipe (in accordance with the usual "dry" method). The resulting refining loss is 0.71% (all refining losses herein are on an anhydrous weight basis, unless otherwise indicated). This is to be compared with an alkali-refining loss for this oil of higher than 2.0%, if similarly refined except without adding any of the pyrophosphate. The resulting product is of satisfactory quality, e. g., for bleaching with fuller's earth or with acid activated clay, and further processing to prepare a shortening.

EXAMPLE 2

Following the procedure of Example 1, except with an oil having 0.5% free fatty acid, using a 20° Bé. lye, reducing the agitation time after addition of the lye to 10 minutes, and heating to a final temperature of 49° C., a 1.16% refining loss is obtained. The foots phase is heavy and tight, and tends to settle out very rapidly. The resulting product is of satisfactory quality.

EXAMPLE 3

This example uses the same oil and follows the procedure of Example 1, except that the oil is heated to 70° C., then the tetrasodium pyrophosphate solution is added, and then the lye is added, all with agitation. Then the mixture is rapidly agitated for 5 minutes to mix the ingredients thoroughly, and then agitated for 5

more minutes with medium agitation at a speech to prevent the foot particles from dropping. Then agitation is stopped and a (5 to 10%) hot water wash is sprayed on the oil; and the mixture is allowed to settle without agitation for 3 hours. The relatively clear portion of the aqueous phase is withdrawn from the bottom (in accordance with the usual "wet" method); a second (about 5%) hot water wash is applied to the oil, and the mixture is allowed to settle for 1½ hours, after which the relatively clear portion of the aqueous phase is withdrawn. Then a third (about 5%) hot water wash is applied, the mixture is allowed to settle for 1 hour, and then all the aqueous phase is withdrawn. A refining loss of 0.56% is obtained, and the resulting product is of satisfactory quality.

EXAMPLE 4

In a repeat run, following the procedure of Example 3, except with an oil having 0.5% free fatty acid, a refining loss of 0.96% is obtained, and the product is of satisfactory quality.

EXAMPLE 5

To a batch of degummed solvent extracted soybean oil (using the same oil as in Example 1), there is added 0.1% of tetrasodium pyrophosphate as a 10% aqueous solution, following which there is added sodium hydroxide in an amount 0.2% in excess of the stoichiometric amount required for neutralization of the free fatty acids in the oil, in the form of a 16° Bé. lye solution. Both the phosphate and lye are at room temperature, with rapid agitation which is continued for 6 minutes after adding the lye; then the temperature is raised to 70° C. with just sufficient agitation to keep the foot particles from dropping to the bottom. The agitation is then stopped and the process continued as described in Example 3. A refining loss of 0.62% is obtained; and the product is of satisfactory quality.

EXAMPLE 6

To a batch of extracted degummed soybean oil having 0.17% free fatty acid, there is added about 1.85% by volume of a saturated solution of tetrasodium pyrophosphate (at room temperature), and then there is added 2.9% by volume of 6° Bé. lye, with agitation at 40° C. The oil may be heated to 80° C. before adding the pyrophosphate and the lye, or after adding both, or intermediate the addition of these two agents. After heating to 80° C., the resulting mixture is settled, and washed by a 10% by weight still water wash. After again settling, the aqueous phase is removed ("wet" method). In this way a refining loss of 0.4% is obtained, and the product is of satisfactory quality. This is to be compared with a refining loss of 1.7% for the same oil refined in the same manner, except without adding any tetrasodium pyrophosphate.

EXAMPLE 7

Following the procedure of Example 6, except using an expeller soybean oil having about 0.5% free fatty acid, and using about 4.0% by volume of 6° Bé. lye, a refining loss of 2.1% is obtained, and the product is of satisfactory quality. This is to be compared with a refining loss of 14.1% for the same oil refined in the same way, except without any tetrasodium pyrophosphate.

This reduction in loss is indeed surprising when one considers that the pyrophosphate is a surface active material, and that the soybean oil already

contains surface active phosphatide material. This oil presents particularly difficult refining problems, and the discovery of the process of alkali-refining this oil in the presence of tetrasodium pyrophosphate is a much desired advance therein. The above examples represent the preferred embodiment of the invention and that which is of the greatest commercial significance at this time.

The following examples and discussions illustrate or show broader aspects of the invention, e. g., as applied to other oils and fats or as to the use of other inorganic phosphate additives. Although tetrasodium pyrophosphate is markedly superior in many instances, other inorganic phosphates may be used to show some improvement as indicated below.

EXAMPLE 8

To a batch of cottonseed oil having 2.0% free fatty acid, there is added about 0.1% of tetrasodium pyrophosphate (as an aqueous solution saturated at room temperature), and then there is added sodium hydroxide in an amount 0.5% in excess of the stoichiometric amount required for neutralization of free fatty acid in the oil, in the form of a 12° Bé. lye solution, all at 80° C. and with rapid agitation for 5 minutes. Then the mixture is settled, and given two still washes with hot water, and after settling the aqueous layer is removed. A 7.8% refining loss is obtained, and the product can be bleached and further processed in the conventional manner. This is to be compared with a refining loss of 12.6% for the same oil refined in the same manner, except without any tetrasodium pyrophosphate.

EXAMPLE 9

A batch of expeller soybean oil having an 0.4% free fatty acid content, is treated with 1.85% by volume of a solution (saturated at room temperature) of trisodium phosphate. There is then added at 40° C. a 12° Bé. lye solution in an amount to provide 0.23% sodium hydroxide in excess of that required to neutralize the free fatty acids. The foot particles settled down well and left a clear oil, the refining loss being 1.1% as compared with a loss of 8.2% when the phosphate is not used.

EXAMPLES 10-17

A series of phosphate compounds were used as additives in alkali-refining and expeller soybean oil having a free fatty acid content of 0.62%, and also an extracted, degummed soybean oil having a free fatty acid content of 0.42%. The Glass Kettle Method was used, except that the foot particles were not finally centrifuged. This method, and the apparatus used for practicing it, is described in "Oil and Soap," vol. 22, page 158 (1945). The alkali was 8° Bé. and used in 0.2% excess and the phosphate additives were all in a 10% aqueous solution and the amount and nature of the phosphate and the refining loss is indicated in the following tables:

Expeller soybean oil

Example No.	Additive	Loss in Refining Per cent
10.	None	13.8
11.	33% Na ₄ P ₂ O ₇	2.6
12.	33% Na ₄ P ₂ O ₇	2.9
13.	33% Na ₄ PO ₇	4.1
14.	33% (NaPO ₄) ₂	0.7

Extracted degummed soybean oil

Example No.	Additive	Loss in Refining
		Per cent
14.	None	3.4
15.	.10% Na ₄ PrO ₄	0.6
16.	.10% Na ₄ PO ₄	1.9
17.	.10% NaPO ₄	1.4
	.10% (NaPO ₄) ₄	0.46

It is preferred to add the phosphate compound to the oil prior to the alkali.

Following the usual alkali-refining procedures as applied to known fats and oils (e. g., as described in the literature), especially vegetable oils, refining losses may be reduced substantially by including a small amount of water-soluble inorganic phosphate compound, preferably one which is surface active. In general, the amount of the phosphate compound should be sufficient to reduce the refining loss, and not so large etc. as to increase it. An amount up to about 0.75% and preferably in the range of about 0.05% to about 0.5% by weight, calculated as anhydrous, and based on the weight of the oil, will generally be suitable. The use of mixtures of the phosphate compounds is included in the invention. Instead the sodium compounds, soluble or dispersible compounds containing other cations, especially the alkali metals, may be used. Generally, the sodium compounds are to be preferred for economic reasons.

In view of the foregoing disclosures, variations and modifications thereof will be apparent to those skilled in the art, and the invention contemplates all such variations and modifications except as do not come within the scope of the appended claims.

I claim:

1. In a process of alkali-refining a fatty glyceride stock by treatment with aqueous alkali, as the essential neutralizing agent for free fatty acids in the stock and separating an aqueous phase containing undesirable impurities and a refined oil phase, the improvement which comprises having present in the refining mixture a small amount up to about 0.75% of an inorganic phosphate compound to reduce the refining losses.
2. The process of claim 1, wherein the phases are formed into separate layers by settling.
3. The process of claim 2, wherein the aqueous phase is drawn off from below the oil phase.
4. The process of claim 1, wherein the fatty glyceride is a soybean oil.
5. The process of claim 1, wherein the phosphate compound is tetrasodium pyrophosphate.
6. The process of claim 1 in which the phosphate is added to the oil as a solution before the alkali is added.
7. The process of claim 1 in which the phosphate is added in an amount within the range of 0.05% to 0.5%.

S. JACK RINI.
